UNITED STATES PATENT OFFICE.

EDWIN B. STIMPSON, OF BROOKLYN, NEW YORK, ASSIGNOR TO EDWIN B. STIMPSON COMPANY, OF BROOKLYN, NEW YORK.

ATTACHMENT FOR RIVET-SETTING MACHINES.

Original application filed November 26, 1921, Serial No. 517,919. Divided and this application filed April 17, 1923. Serial No. 632,715.

To all whom it may concern:

Be it known that I, EDWIN B. STIMPSON, a citizen of the United States, residing at Brooklyn, in the county of Kings and State 5 of New York, have invented certain new and useful Improvements in Attachments for Rivet-Setting Machines, of which the following is a specification.

This invention relates to attachments for 10 rivet-driving machines in which the shanks of the rivets are slit lengthwise to form bifurcations; and the present application has for its object to disclose and claim, in a divisional application based on my copending 15 application Serial No. 517,919 filed November 26, 1921, such an attachment, and one whereby the slit rivets may be fed beneath the driving plunger of the machine so that the jaws or bifurcations of all of the rivets 20 will be similarly positioned, i. e., all of the slits will occupy substantially the same plane, when in position to be driven by the plunger. A different attachment, but one having a similar function, is claimed specifically in said my copending application. 25 Such an attachment not only adds to the finished appearance of the article due to the symmetrical arrangement of the rivet jaws, but is in many cases absolutely necessary by the shape of the finished article. 30 The invention of the present application provides simple, effective means for accomplishing this object.

Other objects and advantages will hereinafter appear.

In the accompanying drawings:

Figure 1 is a front elevation of a portion of a rivet-driving machine with the invention applied thereto;

Figure 2 is a side view of the device shown in Figure 1;

Figure 3 is an enlarged detail view of the invention applied to the machine and showing the driving plunger in lowered position;

Figure 4 is a view similar to Figure 3 but showing the driving plunger in elevated position;

Figure 5 is a plan view, partly sectioned, 50 of the parts shown in Figures 5 and 6; and

Figure 6 is a front and side elevation of the tip of the operating spring.

Referring to the drawings, there is shown a rivet-driving machine of the usual type

comprising a vertically reciprocating plunger 10 operating between guides 11 to drive rivets such as 12 downwardly through an article 13 supported upon an anvil 14 in axial alignment with said plunger 10. On the downward stroke of the plunger a rivet is driven through article 13 and the jaws of the rivet are spread upon the opposite face of the article. The rivets are fed to the driving position beneath plunger 10 and between guides 11 in the usual manner by allowing the rivets to pass down an inclined guide-way 20, upon which they are supported by their heads, until they rest above a horizontal slot 21 in which operates a slide 22. Said slide has a vertical opening 23 therein large enough to receive the lowermost rivet in guide-way 20, and said slide is so connected with the plunger that every time the latter operates to drive a rivet into an article the slide is moved over until the rivet held therein is directly over an inclined slot 25 which terminates adjacent the plunger when the latter is in lowered position. (See Fig. 4). When the plunger is elevated it rises above the lower end of slot 24 and permits the rivet held in the end of the slot to drop between guides 11 into the driving position. As the plunger descends, another rivet is fed by slide 21 into slot 24, said rivet moving to the lower end of slot 24 and abutting against the plunger. The action is then repeated. The hereinbefore described structure is usual in rivet-driving machines.

It is desirable, as previously pointed out, 90 that the rivets be fed to the driving position with their jaws similarly positioned, i. e., with the slits in substantially the same plane. For this purpose there is provided a device which operates to position the rivets 95 properly as each rivet reaches the bottom of slot 24 adjacent the lowered plunger in position to drop to driving position when the plunger is raised. Each rivet is similarly positioned by this device so that when 100 it drops to driving position the place of the slits will be in substantially the same position in every case. The device comprises an operating member in the form of a flat portion 50 having a point or tip 51 fixed near one end of a spring member 52 whose other end is attached to the machine frame. 105 The plunger 10 is provided with a pin 53,

which, when the plunger rises, engages one arm 56 of a lever pivoted at 57 on the machine frame. The end of the other arm 58 of said lever engages a corrugated portion 59 formed in spring member 52, so that as the plunger rises, arm 58 will rotate downwardly from a substantially horizontal position thus causing its end to move inwardly toward the machine and permitting portion 50 to move further into the rivet slit. As the end of arm 58 moves over the corrugations, the portion 50 will be alternately pressed away from the rivet slit and permitted to spring into said slit, thus causing an intermittent movement. When the plunger descends, a spring of any ordinary type may be provided to restore arm 58 to its raised position, overcoming spring 52 to force the latter to ineffective (or Fig. 3) position.

The tip 51 on the free end of spring 52, when the lever is operated as above, contacts with the rivet at the end of the slot 25, waiting to be dropped to driving position when plunger 10 rises. By repeatedly operating flat portion 50 back and forth into and out of contact with the slit end of the rivet-shank, the tip 51, which is necessarily a wedge and twisted slightly to form a screw or spiral, works its way into the rivet slit, and the flat portion 50 exerts a camming action on the rivet until the plane of the slit coincides with the plane of the portion 50. The portion 50 may then operate in and out of the slit freely. The same action is exerted upon each rivet as it comes to position at the end of slot 25. By the time plunger 10 rises above the end of slot 25, lever 56 has been actuated back and forth several times and the rivet-slit has been brought into the plane of portion 50 by the camming action of said portion. Each rivet is therefore similarly disposed as it drops to driving position beneath the plunger.

Variations may be resorted to within the scope of the annexed claims.

I claim:

1. In a rivet-driving machine having means for feeding the rivets to a point adjacent the driving position, each of said rivets having a slit lengthwise through the shank thereof to form bifurcations, means mounted upon said machine for positioning said rivets when adjacent the driving position so that the slits and the bifurcations of the rivets are similarly disposed, said means including a spring member fixed at one end to the machine and carrying a flat member at its other end, and means for intermittently operating said spring member to cause said flat member to enter the slits in the rivets to bring said slits into the plane of said flat member.

2. In a rivet-driving machine having

means for feeding the rivets to a point adjacent the driving position, each of said rivets having a slit lengthwise through the shank thereof to form bifurcations, means mounted upon said machine for positioning the rivets when adjacent the driving position so that the slits and the bifurcations of the rivets are similarly disposed, said means including a spring member fixed at one end to the machine and carrying a flat member at its other end, said spring member normally pressing said flat member toward the slits in the rivets, said machine having a driving plunger, and a movable member mounted on said machine and operated by said plunger and engaging said spring member to operate said flat member intermittently to cause said flat member to enter the slits in the rivets to bring said slits into the plane of the flat member.

3. In a rivet-driving machine having means for feeding the rivets to a point adjacent the driving position, each of said rivets having a slit lengthwise through the shank thereof to form bifurcations, means mounted upon said machine for positioning the rivets when adjacent the driving position so that the slits and the bifurcations of the rivets are similarly disposed, said means including a corrugated spring member fixed at one end to the machine and carrying a flat member at its other end, said spring member normally pressing said flat member towards the slits in the rivets, said machine having a driving plunger, and a movable member mounted on said machine and operated by said plunger and engaging said corrugations to operate said flat member intermittently to cause said flat member to enter the slits in the rivets to bring said slits into the plane of said flat member.

4. In a rivet-driving machine having means for feeding the rivets to a point adjacent the driving position, each of said rivets having a slit lengthwise through the shank thereof to form bifurcations, and means mounted upon said machine for positioning the rivets when adjacent the driving position so that the slits and the bifurcations of the rivets are similarly disposed, said means including a spring member fixed at one end and carrying a flat member at its other end, said machine having a driving plunger, and a lever mounted on said machine and operated by said plunger at one end, said spring member having corrugations positioned progressively farther from the machine, the other end of said lever engaging said corrugations in succession, when said plunger rises, to operate said flat member intermittently and to an increasing degree to cause said flat member to enter the slits in the rivets to bring said slits into the plane of said flat member.

5. In a rivet-driving machine having means for feeding rivets to a point adjacent the driving position, each of said rivets having a slit lengthwise through the shank thereof to form bifurcations, means mounted upon said machine for positioning the rivets when adjacent the driving position so that the slits and the bifurcations of the rivets are similarly disposed, said means including an anchored spring member carrying a flat portion, said spring member normally pressing said flat portion toward the slits in the rivets, said machine having a driving plunger, and a member movably mounted on said machine and operated by

said plunger, said spring member having corrugations positioned progressively farther from the machine, said movably mounted member engaging said corrugations in succession, when said plunger rises, 20 to reciprocate said flat portion by strokes of increasing length to cause said flat member to enter the slits in the rivets to bring said slits into the plane of said flat member, and means for restoring said member 25 to initial position and for disengaging said flat portion from the slits when said plunger descends.

In testimony whereof I affix my signature.
EDWIN B. STIMPSON.
